UNITED STATES PATENT OFFICE.

GEORGE E. SCHULTZ, OF NEW YORK, N. Y.

SAFETY-MATCH.

No. 882,427.

Specification of Letters Patent. Patented March 17, 1908.

Application filed January 12, 1906, Serial No. 295,741. Renewed January 25, 1908. Serial No. 412,635.

To all whom it may concern:

Be it known that I, GEORGE E. SCHULTZ, a citizen of the United States, and a resident of the city of New York, borough of Manhattan, in the county, and State of New York, have invented a new and Improved Safety-Match, of which the following is a full, clear, and exact description:

Many forms of safety matches have been devised in which the match itself carries an ignition composition for use in lighting the match. These have usually been exposed, however, to wear on the outside of the match and they have therefore been so located that if carried in certain ways the ignition material would be rubbed off, and also if the matches were placed in a confined space or pocket there was danger that the burning composition on one match would come in contact with the ignition composition on another and the match or matches take fire accidentally. These matches have also been open to certain other objections.

The principal objects of the present invention are to provide a safety match with an ignition strip, mass or composition so placed that there will be no danger of accidental ignition and no danger of subjecting the igniting composition to wear.

Reference is to be had to the accompanying drawings forming a part of this specification, in which similar characters of reference indicate corresponding parts in all the figures.

Figure 1 is a side elevation showing my invention in a very simple form; Fig. 2 is a view illustrating the manner in which the match is used for lighting, and Figs. 3 and 4 are perspective views showing other forms in which the invention can be constructed.

A match *a* is provided as usual with a burning composition *b*. At a point near its lower end the match is provided with a thickened portion *c* in which I provide a slit *d*. This slit extends preferably at an acute angle from the edge of the match so that when the match is bent from its ends it will break across the wood or other material of which it is constructed on a line extending from the inner end of the slit, the proportions being so calculated that this result will uniformly be obtained. But in order to prevent the match from being broken acciden-

tally at this point the thickened portion is made just wide enough to allow room for the slit and a piece of solid material at the end of the slit only slightly smaller in extent than the balance of the match. In the form shown in Fig. 1 these parts are arranged in a very simple manner, but the forms shown in Figs. 3 and 4 are constructed in a way which I regard as better, the parts being thicker at points near the slit than they are at the inner end of it thereby insuring the breaking of the match at this point. On the lower side of the slit, that is, the side away from the lighting material *b* I place a strip *e* containing the igniting composition, or I mold the igniting composition directly upon the surface of the match at this point. In order to further guard against accidental breakage of the match I have shown two separate means for strengthening the match on the open side of the slit.

In Fig. 3 I have shown a piece of glue *f* or similar material secured to the surfaces of the match so as to assist in holding it in an obvious manner, it being understood that the glue is sufficiently brittle to permit breakage when this is desired.

In Fig. 4 I have shown a strip of paper or fabric *g* pasted or otherwise secured to the edge of the match on the opposite sides of the open end of the slit for the same purpose. The manner of using the match will be readily understood from an inspection of Fig. 2 and need not be described in detail. The main advantages of the match are obtained by any of the three constructions which I have illustrated, but they are more efficiently provided for in the forms shown in Figs. 3 and 4.

Having thus described my invention, I claim:

1. A safety match having an incision extending partly through the body of the match, whereby the match will break on a line extending from the inner end of the incision across the match, and an igniting composition on one of the surfaces of the incision.

2. A match having a thickened portion near one end, and an inclined incision located adjacent to said thickened portion and having an igniting composition on the surface thereof farthest from the lighting composition.

3. A match, the stick of which is adapted to be separated into two parts, said parts having respectively burning and ignition compositions thereon, and the match having 5 means for normally protecting the ignition composition.

In testimony whereof I have signed my

name to this specification in the presence of two subscribing witnesses.

GEORGE E. SCHULTZ.
